DENTURE FASTENER

Robert L. Crevison, Bellefontaine, Ohio

Application June 6, 1955, Serial No. 513,204

7 Claims. (Cl. 32—2)

This invention relates to a novel fastener device adapted to be carried by a denture and having a portion disposed to yieldably engage a part of the gum for effectively retaining the denture properly applied to the gum.

More particularly, it is an aim of the present invention to provide a denture fastening device having an unsecured spring biased part adapted to yieldably grip a recessed gum part for effectively retaining the denture immovably in a properly applied position on the gum.

Another object of the invention is to provide a denture fastening device which is so constructed that the denture can be easily applied to or removed from the gum.

A further object of the invention is to provide a denture holding device which is so constructed that it cannot cause injury to the gum or discomfort to the user yet which due to its unique construction will effectively accomplish its intended result.

Various other objects and advantages of the invention will hereinafter become more fully apparent from the following description of the drawing, illustrating a presently preferred embodiment thereof, and wherein:

Figure 1 is a bottom plan view of a lower denture showing two of the denture holding or retaining devices in applied positions therein;

Figure 2 is an enlarged cross sectional view through the denture, showing the denture in an applied position and taken substantially along a plane as indicated by the line 2—2 of Figure 1;

Figure 3 is an enlarged fragmentary longitudinal sectional view taken substantially along a plane as indicated by the line 3—3 of Figure 1;

Figure 4 is an enlarged fragmentary longitudinal sectional view, taken substantially along a plane as indicated by the line 4—4 of Figure 3, and

Figure 5 is a plan view of a part of the blank, partially formed, from which the denture holding device is constructed.

Referring more specifically to the drawing, for the purpose of illustrating a preferred application and use of the denture holding device, designated generally 7 and comprising the invention, a lower denture of substantially conventional shape has been illustrated and is designated generally 8. Said lower denture 8 has a relatively deep channel 9 extending from end-to-end thereof which opens downwardly or outwardly of the underside of said denture and in which the lower gum 10 is adapted to be received. The upper side of the denture 8 is provided with the usual false teeth, only one of which is illustrated and designated 11. The channel 9 divides the bottom portion of the denture 8 to form an outer wall 12 and an inner wall 13.

The denture 8 is preferably equipped with two holding devices 7, as illustrated in Figure 1, which are disposed in spaced apart relation to one another and which may be located at different distances from the ends of the denture 8. As the holding devices 7 are identical, a description of one will suffice for both.

2

Each holding device 7 includes an elongated strip 14 preferably formed of stainless spring steel having a laterally flared enlargement at one end thereof in the form of a crosshead, as seen at 15. Approximately one half 5 of the strip 14, constituting the end portion disposed remote from the crosshead 15 is embedded in the outer wall 12 of the denture 8. Said denture 8 may be formed of any suitable molded material, such as a plastic, and the end portion 16 of the strip is embedded and anchored in 10 the wall 12 during the molding operation of said denture and extends upwardly within the wall 12 from adjacent a portion of its bottom edge, as seen in Figure 2, to substantially the top central portion 17 of the channel 9, at which point the strip 14 emerges from the body of the denture 8 into the channel 9 thereof. The strip 14 is bowed into substantially inverted U-shape or arch shape form so that the other exposed end portion 18 thereof, to which the crosspiece 15 is connected, extends downwardly in the channel 9 on the inner side of the inner wall 13 of the denture, as seen in Figures 2 and 3. The crosspiece 15 is supported by the strip 14 in the channel 9, near its open bottom and longitudinally thereof and on the inner side of and adjacent the inner denture wall 13. As best 20 illustrated in Figures 2 and 4, the ends and longitudinal edges of the crosspiece 15 are rounded and flared as seen at 19 so as to extend toward the wall 13.

As best illustrated in Figures 2, 3 and 4, the wall 13 is provided with a longitudinally extending inwardly opening recess 20 which is disposed somewhat above and substantially coextensive with the crosspiece 15. A longitudinally bowed elongated strip, preferably of stainless spring steel 21, has the intermediate portion of its outer convex side suitably secured to the side of the strip end 18 which faces toward the wall 13. Said spring 21 has a bottom edge underlying or disposed outwardly with respect to the upper edge portion of the crosspiece 15 and an upper edge disposed thereabove in a position to loosely fit in the recess 20, and is of a length less than the length of said recess, as seen in Figures 3 and 4. The ends of the 30 spring 21 bear against the bottom or bed of the recess 20 and have slidable engagement therewith, as will herein- 35 after become apparent.

The bottom gum 10, after removal of the natural teeth therefrom, has a ridge 22 on the inner side thereof and which forms a longitudinally extending indentation or groove in the inner side of the gum 10, beneath said ridge 22, as seen at 23 in Figure 2.

As the denture 8, equipped with the two holding devices 7, is displaced downwardly within the mouth for application to the lower gum 10, it will be readily apparent that the gum 10 will be received in the downwardly opening denture channel 9. During the initial stage of the application of the denture 8 to the gum 10, the rounded bottom edge 19 of the crosspiece of each holding device 7 will initially contact the upper portion of the inner side of the gum 10 and will be deflected or displaced outwardly thereby toward the wall 13 to thus stress or tension the strip portion 18. This outward displacement of the crosspiece 15 will also cause the spring 21 to be displaced inwardly of the recess 20. As the ends of the spring 21 contact the inner wall or bed of the recess 20, inward displacement of the spring into said recess will cause a straightening of the spring and a lengthening thereof, so that the spring ends by sliding contact with the inner wall 60 of the recess 20 will slide toward the ends of said recess and the spring 21 will thus be distorted toward a straight line position and placed under tension. The tensioning of the strip portion 18 and spring 21, as previously described, will reach a maximum as the crosspiece 15 rides downwardly over the ridge 22. After the crosspiece or 65 gum gripping part 15 of the fastening device 7 clears the ridge 22, the resiliency of the strip leg 18 and the 70

tensioned spring 21 will combine to spring bias said gum gripping portion 15 away from the inner wall 13 to cause the part 15 to seat in the groove 23 of the inner side of the gum 10 and which is located immediately beneath the ridge 22. Thus, the two gum gripping parts 15 of the denture fastening devices 7 will effectively function to retain the denture 8 immovably positioned on the gum 10.

However, it will also be readily apparent that an upward pull on the denture 8 will cause the gripping members 15 to ride upwardly over the ridge 22 and to yield toward the inner wall 13, as previously described, for removing the denture. The rounded top and bottom edges and ends 19 of the gripping members 15 will enable said members to slide relative to the inner side of the gum 10 without scraping the gum or otherwise causing discomfort to the user.

While the denture retaining means has been illustrated and described in connection with a lower denture, it is to be understood that the use thereof is not limited to the lower denture and that the retaining devices are likewise capable of use with upper dentures.

Various modifications and changes are contemplated and may obviously be resorted to, without departing from the spirit or scope of the invention as hereinafter defined by the appended claims.

I claim as my invention:

1. In combination with a denture having an outwardly opening gum receiving channel and including an outer wall and an inner wall between which said channel is disposed and a body portion connecting said walls and defining the bed of the channel; a denture retaining device comprising an elongated flexible strip, said strip being bowed to provide a first leg and a second leg and an arcuate intermediate portion from which said legs project, said first leg being embedded and anchored in said outer denture wall, said second leg being disposed in the denture channel on the inner side of and adjacent the inner denture wall, said second leg being spring biased by the resiliency of said strip toward the anchored first leg and away from the inner denture wall, and an elongated crosspiece connected to the distal end of said second leg and disposed longitudinally of said channel and supported loosely therein by said second leg and adapted to yieldably bear against a portion of an inner side of a human gum which is disposed in the denture channel for yieldably retaining the denture applied to the gum.

2. In a denture holding device as in claim 1, said intermediate portion of the strip being partially embedded in the body portion of the denture and partially exposed in the bed portion of the channel.

3. In a denture holding device as in claim 2, said cross-

piece being of a length substantially greater than the width of said second leg and having longitudinal edge portions and end portions rounded and flared toward said inner denture wall.

5. In a denture holding device as in claim 1, an elongated longitudinally bowed spring strip disposed between said second leg and the inner denture wall and having the intermediate portion of the convex side thereof secured to said second leg adjacent the distal end thereof and having end portions slidably bearing against said inner wall for spring biasing the crosspiece inwardly of the channel and away from said inner wall.

6. In a denture holding device as in claim 4, said inner denture wall having an elongated longitudinally extending inwardly opening recess receiving said spring strip and having a bed portion slidably engaged by the ends thereof.

7. In combination with a denture having an outwardly opening gum receiving groove and including an outer wall and an inner wall between which said groove is disposed and a body portion connecting said walls and having a part defining the bed of the groove; a denture retaining device comprising an elongated flexible strip, said strip being bowed to provide a first leg and a second leg and an arcuate intermediate portion from which said legs project, said first leg being embedded and anchored in said outer denture wall, said second leg being disposed in the denture groove on the inner side of and adjacent the inner denture wall, an elongated crosspiece connected to the distal end of said second leg and disposed longitudinally of said groove and supported loosely therein by said second leg and adapted to bear against a portion of an inner side of a human gum which is disposed in the denture groove, and an elongated arcuately bowed spring strip disposed between said second leg and the inner denture wall and crosswise of the second leg, said spring strip having the intermediate portion of its convex side secured to the second leg adjacent the distal end thereof and having end portions bearing against and slidably engaging said inner wall for spring biasing said crosspiece inwardly of the groove and away from said inner wall, said crosspiece being yieldably held against a portion of the inner wall of the gum beyond a ridge of the inner side of the gum for retaining the denture in an applied position on the gum.

8. In a denture holding device as in claim 6, said inner denture wall having a longitudinally extending inwardly opening recess in which said spring strip is loosely received and having a bed against which the ends of the spring strip slidably engage.
